US0D1069159S

(12) **United States Design Patent** (10) **Patent No.:** **US D1,069,159 S**
(45) **Date of Patent:** **** Apr. 1, 2025**

(54) **CELL CULTURE BAG**

(71) Applicant: **Toyo Seikan Group Holdings, Ltd.**,
Tokyo (JP)

(72) Inventor: **Ryo Suenaga**, Yokohama (JP)

(73) Assignee: **TOYO SEIKAN GROUP HOLDINGS, LTD.**, Tokyo (JP)

(**) Term: **15 Years**

(21) Appl. No.: **29/891,313**

(22) Filed: **May 4, 2023**

Related U.S. Application Data

(62) Division of application No. 29/778,203, filed on Apr. 12, 2021, now Pat. No. Des. 1,008,486.

(57) **CLAIM**

The ornamental design for a cell culture bag as shown and described.

DESCRIPTION

FIG. 1 is a front view of a cell culture bag showing a first embodiment of my new design, a rear view being identical to the front view thereof;

FIG. 2 is a right side view thereof, a left side view being identical to the right side view thereof;

FIG. 3 is a plan view thereof;

FIG. 4 is a bottom view thereof;

FIG. 5 is a perspective view thereof;

FIG. 6 is a partial enlarged view taken from area 6 in FIG. 3;

FIG. 7 is an enlarged cross-sectional view along the line 7-7 in FIG. 6;

FIG. 8 is an enlarged cross-sectional view along the line 8-8 in FIG. 3;

FIG. 9 is a front view of a cell culture bag showing a second embodiment of my new design, a rear view being identical to the front view thereof;

FIG. 10 is a right side view thereof, a left side view being identical to the right side view thereof;

FIG. 11 is a plan view thereof;

FIG. 12 is a bottom view thereof;

FIG. 13 is a perspective view thereof;

FIG. 14 is a partial enlarged view taken from area 14 in FIG. 11;

(Continued)

FIG. 15 is an enlarged cross-sectional view along the line 15-15 in FIG. 14; and,
 FIG. 16 is an enlarged cross-sectional view along the line 16-16 in FIG. 11.

1 Claim, 8 Drawing Sheets
